To all whom it may concern:

Be it known that I, LUCIAN FLANDERS HOWE, a citizen of the United States, residing in the city, county, and State of New York, have invented and produced a new and original Design for a Skirt-Protector, of which the following is a specification, reference being had to the accompanying drawings, forming part thereof.

- 15 Figure 1 represents a face view of a piece of a skirt-protector or dress-trimming embodying my design. Fig. 2 represents a section thereof on line xx , Fig. 1.

In the drawings, A designates a piece of skirt-protector or dress-trimming, consisting 20 of the head B, the brush C, which is pendent from the bottom thereof, and a raised edging D on the upper end thereof, said edging being composed of loops and a centrally-disposed rib.

Having thus described my invention, what I claim as new, and desire to secure by Letters Patent, is—
